UNITED STATES PATENT OFFICE.

FRANK JOSEPH PEREY, OF BROOKLYN, NEW YORK.

TURNSTILE.

1,307,317.

Specification of Letters Patent. Patented June 17, 1919.

Application filed March 14, 1917. Serial No. 154,774.

To all whom it may concern:

Be it known that I, FRANK J. PEREY, a subject of the Queen of Holland, residing at the city of New York, borough of Brooklyn, county of Kings, State of New York, have invented certain new and useful Improvements in Turnstiles, of which the following is a specification.

My invention relates particularly to improvements in the design and construction of turnstiles.

There are many serious objections found to exist in turnstiles of various types now in common use and among these may be mentioned, first, the comparatively intricate and complicated mechanism employed, which is made up of a large number of parts or elements requiring great care and skill in adjustment. Further, owing to the peculiar arrangement and assembling of such mechanism, the machine has to be practically disorganized for purposes of examination and repair, and while the latter, in many cases, may prove of little or no consequence, the time occupied in taking the machine apart and putting it together again makes a trifling breakdown a matter of serious consequence, particularly, if it occurs during rush hours.

As ordinarily constructed, the greater portion of the operating mechanism is located in the base of the pedestal forming the inclosing casing of the machine and this pedestal is bolted or otherwise secured, as firmly as possible to the floor, to give the machine the necessary rigidity to withstand all sorts of blows, strains and pressures, to which it is ordinarily subjected by the ever-varying methods adopted by people in rotating the projecting arms thereof. The operating mechanism being thus located in the base of the machine, removal of the pedestal bolts or other fastenings is essential as the first step for either inspection or repair. In addition to this disadvantage, there is a further resulting objectionable feature involved which consists in the necessary employment of a central vertical shaft extending usually throughout the length of the pedestal, as the means of operatively connecting the turnstile arms with the mechanism by which their movement is limited and controlled. Such a shaft must be well mounted and it and its bearings constitute an item of considerable expense, in addition to the more serious objection of its failing,

for many obvious reasons, to rotate freely with little or no friction.

There is further objection to the type of machine above referred to, in that the pedestal and its enlarged base, stand and occupy valuable space within the passageway controlled by the turnstile and form an obstruction over which people frequently trip or come into violent collision in the rush to get through.

The present invention is designed to overcome the above mentioned and other difficulties experienced with turnstiles now in general use and to this end, I have produced the machine illustrated in the accompanying drawings which, as therein embodied, is the best form at present known to me for carrying my invention into effect.

In these drawings:

Fig. 1, is a view in side elevation of a turnstile constructed in accordance with my invention.

Fig. 2 is a sectional view taken on a plane parallel to the plane of Fig. 1 and centrally of the machine.

Fig. 3, is a top plan view of the machine with the cover plate of the casing removed;

Fig. 4, a bottom plan view of the rotary member or element of the machine removed from the casing.

Fig. 5 is a detail view of the locking bolt of the rotary member;

Fig. 6, is a detail view of the tension shoe;

Fig. 7, is a detail view of the ratchet pawl;

Fig. 8, is a detail view of one of the four gravity shutters which are carried by the rotating member of the machine and operate with the locking notches therein.

Fig. 9, is a detail view showing the cushion inserts of the locking-bolt bearings.

Referring now to these drawings, 1, represents the outer inclosing casing of the operating mechanism which is provided with a removable top plate 2, secured by screws or any other suitable fastenings 3. This casing may be supported from the ground or floor by means of a pedestal 4, or, if preferred, the pedestal may be omitted and the casing attached to a side wall or shelf, projecting from such wall. Oppositely disposed ears 5, 5, are provided for a side wall attachment of the casing and webbed portions 6, 6, for attachment to a shelf. Both the ears and webbed portions have holes formed therein for the passage of fastening

- bolts or screws. When attached either to a side wall or shelf, clearance of course must be provided to permit free and unobstructed rotation of the arms of the turnstile and in 5 either form of mounting, it is customary to provide a suitable housing on the inner side of the wall, inclosing the space occupied by the rotating arms of the turnstile, as indicated by dotted lines in the drawings.
- 10 The casing 1, is cylindrical as shown and is counter-bored centrally at 7, to provide a flat bearing surface 8, to receive the rounded end of a short spindle 9, of the rotating member 10, of the machine. The member 10 is 15 reduced at its upper end 11, and projects through an opening in the top plate of the casing to serve as a support for the arms 12, of the turnstile, there being four of such arms arranged in the usual manner at 90° 20 apart.

Controlling and limiting the direction of rotation of the member 10, there is a ratchet and pawl 13 and 14. The ratchet teeth are formed in the lower face of the member 10, 25 concentric with its axis and the coöperating pawl 14, is carried by a removably block 15, bolted to the casing. A spring 16 serves to maintain the pawl in operative position with the ratchet.

30 It is found desirable, in order to adapt the machine to passageways of various forms and constructions, to provide a convenient and ready adjustment for setting the machine to rotate either toward the right or 35 toward the left, as occasion may require. To accomplish this in the present machine, all that is necessary is to remove the block 15, and give the pawl 14 a half turn, the effect of which is to reverse the ratchet. As the 40 block is outside of the casing and is accessible from the bottom of the machine, this simple adjustment may be readily made by any one without the aid of a skilled workman and the machine will instantly respond to rotation in the direction for which the ratchet 45 is set, no change or adjustment of any other part of the mechanism being required.

The locking mechanism, while differing in construction and operation from that heretofore employed in machines of this class, is 50 designed to effect substantially the same result, *i. e.*, to come into action at each quarter turn of the machine, that is to say, as each of the arms in its travel reaches the point at 55 which it extends directly across the passage the machine is arranged to control.

As shown, the rotating member 10, is provided with four notches or recesses 17, spaced 90° apart and arranged in line with the 60 turnstile arms 12. Pivoted directly above each notch there is a gravity shutter 18, so shaped and arranged as to normally close the notch. In order to check the tendency of the shutters to vibrate or swing, the opening 65 through which the shutter pivot passes is

elongated, as indicated at 18^a, permitting the shutter to drop and rest on the bottom of the casing, and in addition to this, the shutter is provided with a straight or flat lower edge which, on coming to rest against the 70 bottom of the casing, further acts to check the tendency of the shutter to swing back and forth.

Adapted to coöperate with the series of notches 17, above referred to, there is a locking bolt 19, which, under the tension of a spring 20, is normally advanced toward the rotating member and lying in the plane of the notches in such member, engages the same successively as the member is rotated. 75 The end of the bolt 19, under the action of its spring 20, is pressed closely against and rides on the peripheral surface of the rotating member and as one of the locking notches moves into line with the bolt, the 80 shutter covering the notch is caused upward by contact with the bolt, thus permitting the spring 20 to shoot the bolt forward into engagement with the notch and lock the machine against further rotation. 85

In order to relieve the machine of the shock resulting from the sudden stopping of the rotating member, as the bolt engages and locks the same, provision is made for permitting the bolt to yield laterally to a 90 limited extent. This is accomplished by employing a guide sleeve 19^a, of approximately inverted V-shape in cross section, in which the bolt has free back and forth movement, and which is held in position in the recess 100 of the machine casing, by two blocks of rubber 19^b, 19^b, as shown in Fig. 9.

The release of the machine by disengaging the locking bolt, may be brought about in various ways. The usual means 105 consists of a pivoted lever, such as is illustrated at 21, the upper end of which is operatively connected with the bolt in such manner that the pull of an attached cord 22, or the depression of a connected foot lever 23, withdraws the bolt from the locking recess of the rotating member, leaving 110 the machine free to rotate.

The withdrawal of the locking bolt as just described, permits the shutter 18, to swing 115 back into position closing the notch against the return of the bolt, should the operator or attendant immediately release the foot lever. By this arrangement it will be seen how very little time and attention is required to unlock the machine, a quick pull on the cord or downward stroke of the foot lever only being necessary, and once this is effected, accidental relocking is made impossible through the instantaneous operation 120 of the shutter.

It is both important and desirable to relieve those passing the turnstile of as much of the burden and inconvenience of operating the machine as possible, and to this end, 130

I have provided for semi-automatic action through the last part of each quarter revolution, so that it is only necessary for a person passing, to turn the machine through about an eighth of a revolution and thereafter the machine becomes self-acting. The device or mechanism by which this is accomplished is utilized also to make definite and certain the operation of the locking device. This is done by causing it to check or retard the movement of the rotary member, as a locking notch therein comes into line with a locking bolt, and to then yieldingly maintain the rotary member against further rotation, as the locking bolt is advanced and enters the notch thereof.

The results above referred to, are brought about by means of a V-shaped shoe 24, which is advanced toward the rotating member by a spring 24^a, and as designed, is adapted to coöperate successively with a series of four V-shaped recesses or pockets 25 formed therein. Anti-friction rollers 26, arranged between the pockets and mounted at or adjacent to the periphery of the rotating member, facilitate coöperation between the shoe and the pockets. The pins 27 on which these rollers are mounted are loosely set in, so as to permit ready withdrawal if desired, through an opening 28, in the cover plate, for the purpose of removing the rollers. The cover plate of the casing serves to prevent the pins from working up or jumping out during the operation of the machine.

From the foregoing it will be seen, that normally, or when the machine is not in operation, it is locked against rotation and to release it for operation by a person passing, the ticket seller or other attendant, by means of either the foot-lever 25, or the cord 22, throws the free end of the lever 21, toward the right, as viewed in Figs. 1 and 2, withdrawing the bolt 19, from the notch in the rotating member 10, leaving the latter yieldingly held only by the friction shoe 24. The operation as far as described, serves to effect the full release of the machine, and relocking, either automatically or by the attendant, before the completion of the operation, is prevented by the shutter 18, closing the notch 17, against the reentrance of the locking bolt. The person passing, either by grasping or pressing against the turnstile arm 12, barring the passage, rotates the member or head 10, causing the shoe 24 to be cammed rearward, in opposition to its spring 24^a, riding out of the pocket 25, it engages and, as the roller 26, passes the point of the V-shaped shoe, the latter, under the influence of its spring, immediately enters the next pocket of the rotating member 10. The advance of the shoe, as just described, serves not only to accelerate and complete the movement of the head or member 10, but also operates to check such movement at the

moment the next locking notch 17, comes in line with the locking bolt, permitting the latter, which first cams up the shutter 18, to be shot into the notch, under the action of the spring 20, and the machine is then ready for the next operation.

Having, therefore, described my invention, I claim:

1. A turnstile comprising a single rotatable member, having the arms of the turnstile fixed to its upper end and provided with locking notches corresponding in number and spacing with the said arms, a spring actuating locking bolt adapted to automatically engage each successive notch, means for disengaging the bolt to free the rotating member, and an automatic check on the return of the locking bolt co-acting to prevent reengagement until the turnstile has performed a complete operation. 85

2. A turnstile comprising a single, rotatable member, having the arms of the turnstile fixed to its upper end and provided with locking notches corresponding in number and spacing with the said arms, a spring actuated locking bolt coöperating with the said notches, and a gravity catch automatically interposed between the bolt and the notch from which it is withdrawn to prevent re-locking of the rotary member until 95 the turnstile has performed a complete operation.

3. A turnstile comprising a single rotatable member, having the arms of the turnstile fixed to its upper end provided with locking notches corresponding in number and spacing with the said arms, a spring actuated locking bolt coöperating with the said notches, and a movable shutter operating by gravity to close each notch against 105 the return of the bolt as the latter is withdrawn therefrom.

4. A turnstile comprising a single rotatable member, having the arms of the turnstile fixed to its upper end and provided with locking notches corresponding in number and spacing with the said arms, a spring actuated locking bolt adapted to automatically engage each successive notch, a spring tension device coacting with a shaped portion 115 of the periphery of the rotating member to successively advance and yieldingly maintain the notches thereof in line with the locking bolt, means for disengaging the bolt to free the rotating member, and a shutter to 120 guard each notch to prevent reseating of said bolt.

5. A turnstile comprising a single rotatable member, having the arms of the turnstile fixed to its upper end and provided with locking notches corresponding in number and spacing with the said arms, a spring actuated locking bolt adapted to automatically engage each successive notch, a spring advanced friction shoe, coacting with 130

shaped recesses formed in the peripheral face of the rotating member to first advance the said member and then yieldingly check and maintain it in position with the locking notches in line with the locking bolt, means for disengaging the bolt to free the rotating member, and a shutter to guard each notch to prevent reseating of said bolt.

6. A turnstile comprising a single rotatable member, having the arms of the turnstile fixed to its upper end and provided with locking notches corresponding in number and spacing with the said arms, a spring actuated locking bolt coöperating with the 10 said notches, means for disengaging the bolt to free the rotating member, a ratchet formed in part with the said member, and a reversibly mounted pawl, engaging the 15

ratchet to control the direction of rotation thereof.

20

7. A turnstile comprising a single rotatable member, having the arms of the turnstile fixed to its upper end and provided with locking notches corresponding in number and spacing with the said arms, a spring 25 actuated locking bolt coöperating with the said notches, means for disengaging the bolt to free the rotating member, ratchet teeth formed in the lower face of said member, and a pawl reversibly mounted engaging the 30 same and controlling the direction of rotation.
